COMBINED REFRIGERATOR AIR FRESHENER AND DEODORIZER

Morris Friedman, New York, N.Y., and Andrey V. Mackey, Ambler, Pa., assignors to Minerware, Inc., New York, N.Y., a corporation of New York, and H.M.S. Associates Co., Willow Grove, Pa., a corporation of Pennsylvania

Filed Apr. 17, 1963, Ser. No. 74,478

Term of patent 3½ years

(Cl. D16—2)

Fig. 3.

Fig. 1.

Fig. 2.

FIG. 1 is a front elevational view of a combined refrigerator air freshener and deodorizer showing our new design;

FIG. 2 is a rear elevational view of the combined refrigerator air freshener and deodorizer of FIG. 1; and

FIG. 3 is a transverse sectional view taken along the lines 3—3 on FIG. 2.

We claim:

The ornamental design for a combined refrigerator air freshener and deodorizer, substantially as shown.
